DESIGN FOR A LIGHTING UNIT

August Bartschat, Milwaukee, Wis.

Application March 27, 1933. Serial No. 47,591

Term of patent 7 years

To all whom it may concern:

Be it known that I, AUGUST BARTSCHAT, a citizen of the United States, residing at 1612 West Hopkins Street, in the county of Milwaukee and State of Wisconsin, have invented a new, original, and ornamental Design for a Lighting Unit, of which the following is a specification, reference being had to the accompanying drawing, forming part thereof.

Fig. 1 is a perspective view of the globe, looking from the bottom, and Fig. 2 is a plan view thereof, showing my new design.

The globe, as shown, is open at both its top and bottom and is circular in cross-section, and is characterized by the double beveled sections located between and connecting the neck and shoulder portion of the body.

I claim:

The ornamental design for a lighting unit, as shown and described.

AUGUST BARTSCHAT.
